UNITED STATES PATENT OFFICE.

CURT J. BALTHASAR, OF NEW YORK, N. Y., ASSIGNOR OF ONE-HALF TO
JOHN W. FRYER, OF SAME PLACE.

VALVE FOR STEAM-RADIATORS.

SPECIFICATION forming part of Letters Patent No. 619,264, dated February 14, 1899.

Application filed March 1, 1898. Serial No. 672,132. (No model.)

To all whom it may concern:

Be it known that I, CURT J. BALTHASAR, of New York city, county and State of New York, have invented an Improved Valve for Steam-Radiators, of which the following is a specification.

This invention relates to an improved valve for steam-radiators which permits the radiator to be readily coupled to the steam-pipes and in which both the inlet and exit ports are simultaneously opened and closed by a double arrangement of valve-disks on a common valve-stem, thus greatly simplifying the operation of turning the steam on or off.

In the accompanying drawings, Figure 1 is a vertical section, partly in elevation, of my improved valve on line 1 1, Fig. 2, and showing it coupled to a radiator. Fig. 2 is a section, partly in elevation, of the valve on line 2 2, Fig. 1, and showing the valve-disks in a different position; and Fig. 3 is a bottom view of the valve.

The letter *a* represents the valve-casing, divided by two transverse perforated partitions *a'* *a''*, constituting inlet and intermediate ports, into three chambers *a⁴* *a⁵* *a⁶*. The valve-stem *b* is threaded at *b'* into the valve-cap and carries two valve-disks *b²* *b³*. Of these the lowermost disk *b²* is fitted upon the stem within chamber *a⁶* and is adapted to be seated when lowered upon the perforated bottom *a³* of the valve-casing, which constitutes the exit-port, while when the disk *b²* is raised it will close the opening in partition *a''*, Fig. 1. Fingers *b⁴*, projecting upwardly from valve-disk *b²* and into the openings of partitions *a'* *a''*, properly guide the valve in its motion.

The upper valve-disk *b³* sits yieldingly upon its stem within chamber *a⁴* and is held against an abutment or sleeve *c* by a spring *c'*. When lowered, this upper valve-disk *b³* seats upon port *a'*, while when raised it is received within the upper part of chamber *a⁴*.

The uppermost chamber *a⁴* connects directly with a leg *a⁸*, which is adapted to be coupled to the steam-supply pipe, while the lowermost chamber *a⁶* connects by port *a³* with an elbow *a⁷*, which is adapted to be coupled to the return-pipe. The upper or transverse

arm of this elbow is arranged beneath chamber *a⁶* and at right angles to leg *a⁸*.

The chambers *a⁵* *a⁶* communicate with a laterally-extending arm *a⁹* of casing *a*, which is adapted to be coupled to a steam-radiator *A* by coupling *d*. The arm *a⁹* is divided into an upper inlet-passage *a¹⁰* and a lower return-passage *a¹¹* by a lateral extension of partition *a²*, that forms a diaphragm within such arm. This diaphragm connects with a corresponding diaphragm *d'* of coupling *d*, which is thus also divided into an upper inlet-passage *d²* and a lower return-passage *d³*.

To turn on the steam, Fig. 1, the valve is raised so that the disk *b³* will open inlet-port *a'*, while disk *b²* will open exit-port *a³* and close intermediate port *a''*, so as to cut off direct communication between chambers *a⁵* *a⁶*. The circulation will be as follows: from leg *a⁸* to chamber *a⁴*, through inlet-port *a'* to chamber *a⁵*, thence through passages *a¹⁰* *d²* to radiator *A*, and back through passages *d³* *a¹¹*, chamber *a⁶*, exit-port *a³*, and elbow *a⁷*.

To shut off the steam, Fig. 2, the valve is lowered, when the port *a'* will be closed by disk *b³* and the port *a³* will be simultaneously closed by disk *b²*, while the intermediate port *a''* will be open.

It will be seen that by my invention both the steam inlet and exit ports are controlled by the motion of a single valve-stem and that the valve-casing is coupled to the radiator by means of a single coupling, thus avoiding a multiplicity of connecting-pipes.

What I claim is—

A valve for steam-radiators composed of a casing having an inlet-port, an exit-port, an intermediate perforated partition, a water-inlet leg communicating with the inlet-port, an exhaust-elbow communicating with the exit-port, and having an upper transverse arm arranged at right angles to the inlet-leg, and a valve-stem having a pair of valve-disks adapted to engage the ports, substantially as specified.

CURT J. BALTHASAR.
